UNITED STATES PATENT OFFICE

2,003,110

RADIO RECEIVING SYSTEM

Paul O. Farnham, Boonton, N. J., assignor, by
mesne assignments, to Radio Corporation of
America, New York, N. Y., a corporation of
Delaware

Application November 4, 1932, Serial No. 641,280

7 Claims. (Cl. 250—20)

This invention relates to radio receiving systems and more particularly to systems of the automatic gain control type.

It has been found desirable in the high gain receivers of this type to provide an additional automatic control which operates to cut off all receiver output in the absence of a radio signal strong enough to override the prevailing "noise level" of the locality where the receiver is operated.

Methods and circuit arrangements for accomplishing this general result are described and claimed in my copending applications Ser. No. 524,383, filed March 21, 1931, Ser. No. 585,593, filed January 8, 1932, Ser. No. 603,849, filed April 7, 1932, and Ser. No. 641,278, filed November 4, 1932.

In accordance with the inventions described in the three later cases, the detector and/or audio amplifier are normally biased to suppress transmission of signals and a direct current amplifier or relay tube is provided to remove the transmission suppression bias when the strength of the received carrier wave rises above a predetermined level, the direct current voltage impressed on the relay tube being obtained by rectification of the amplified carrier wave voltage.

An object of the present invention is to provide in a radio receiver system, improved methods of and circuit arrangements for the automatic control of an operating characteristic of the receiver system in accordance with the magnitude of the radio input to the system. An object is to provide, in a radio receiver, improved methods of and circuit arrangements for suppressing all receiver output when the amplitude of the carrier wave to which the receiver is tuned falls below a predetermined value. A further object is to provide a radio receiver system in which a single tube may perform the functions of the direct current amplifier or relay tube of a noise suppression system and also may serve as the detector and as a source of automatic gain control bias. A further object of the invention is to provide a noise suppression system for radio receivers which does not affect the receiver operation so long as the received radio signal is above a predetermined magnitude, and which provides a sharp cut off for all receiver output when the received radio signal falls below that value.

These and other objects of the invention will be apparent from the following specification when taken with the accompanying drawing in

which Figs. 1 and 2 are fragmentary circuit diagrams of embodiments of the invention.

In the drawing, the reference character 1 identifies a radio frequency amplifier, including one or more vacuum tubes, which receives carrier wave energy from an appropriate collector structure and which works into a detector and audio amplifier or other load circuit. The exact design and construction of the radio amplifier are not a part of the present invention, and only 10 the last amplifier tube 2 is illustrated.

The tuned output circuit 3 of the last amplifier stage is coupled to the tuned input circuit 4 of the detector and automatic control stage of the receiver, the radio voltage E_0 which is built 15 up across the primary circuit 3 establishing a radio voltage E across the secondary circuit 4. The single tube 5 of the combination detector-control stage may be a tube known as "Type 55", and includes a pair of rectifying anodes A_1 , A_2 , a 20 control grid G, plate P and a cathode K.

Referring first to the circuit elements which cooperate with the tube 5 to give the stage the function of a detector and an audio frequency amplifier, the high potential terminal of the 25 tuned input circuit 4 is directly connected to the anode A_2 , and the opposite terminal is connected to the cathode K through an audio frequency resistance 6 and an audio frequency by-pass condenser 7, the resistance 6 being by-passed 30 for radio frequency by a condenser 8. The audio frequency voltage developed by diode rectification across the resistance 6 is impressed upon the control grid G through a filter comprising resistance 9 and a radio frequency condenser 10. 35 The plate circuit includes the primary winding of an audio frequency transformer 11, preferably provided with means such as a shunt resistance 12 and adjustable tap 13 for controlling the output level of the receiver system, and a source 40 of direct current potential $+B$ which is connected to ground or $-B$ through the voltage divider formed by resistances 14, 15. The cathode K is connected to ground through a resistor 16 which is by-passed for audio frequency by the 45 condenser 17. A direct current path for impressing a bias voltage between the anode A_2 and the cathode K is completed by the resistance 18 which is connected between the resistance 6 and the junction of the resistances 14, 15, of the 50 voltage divider.

The flow of plate current through the cathode resistor 16 will establish a potential drop E_1 which places the cathode K at a more positive direct current potential than that of ground or 55

—B. The direct current voltage E_2 across the voltage divider 14, 15 gives rise to a potential E_3 across resistance 16 which applies a positive potential to the anode A₂.

5 The bias voltage on the anode A₂ is equal to the difference of the voltages E_1 and E_3 . The voltage E_3 and the value of resistance 16 are so chosen that, when the input voltage E is zero, a sufficient plate current will flow in the tube 10 5 to make the voltage E_1 greater than the fixed voltage E_3 . In other words, the plate current has a normal value in the absence of received signals which is sufficient to maintain the anode A₂ and the control grid G at direct current potentials which are negative with respect to the cathode. It therefore follows that small peak 15 values of E less than $E_1 - E_3$ will not be rectified in the anode A₂-cathode circuit and hence no audio frequency voltage will be developed across the resistor 6.

20 Attention is directed to the fact that the connection between the audio frequency resistance 6 and the grid G will impress both the rectified audio voltage and the rectified direct current voltage upon the grid G, thus causing the tube 25 5 to function as an amplifier for any direct current voltage developed across resistance 6. This amplified direct current voltage operates to reduce or remove the bias voltages normally impressed upon the anode A₂ and the grid G. When 30 the peak value of the radio input voltage E exceeds the bias voltage $E_1 - E_3$ on the anode A₂, rectification takes place in the circuit including the elements A₂, G and an additional negative 35 bias is thus impressed upon the control grid, which bias effects a reduction in the plate current flow. The consequent reduction in the voltage E_1 across resistance 16 removes the initial bias $E_1 - E_3$ on the anode A₂, and the normal 40 diode detection then takes place in that circuit. The direct current voltage developed across resistance 6 by rectification, together with the decrease in the voltage E_1 across the cathode resistance 16 serves to maintain the control grid 45 bias at a value suitable for audio frequency amplification.

50 A bias voltage for automatically controlling the gain of amplifier 1 is developed between anode A₁ and cathode K by connecting anode A₁ to the tuned primary circuit 3 through a radio frequency condenser 19 and to ground through a resistance 20. The anode terminal of resistance 20 is connected through a filter comprising resistance 21 and condenser 22 to the lead 23 which 55 extends to the control grid circuits of the tube or tubes of amplifier 1.

60 It is desirable that the magnitudes of the radio voltages, E and E_0 , be so related that when the detector input E is increased to that value sufficient to make the voltage drop E_1 across the cathode resistance 16 equal to the fixed bias component E_3 , the peak voltage E_0 on the automatic gain control anode will be equal to E_1 , and thus initiate the action of the automatic gain 65 control. To make the voltage E_0 greater than E, the inductance of the primary tuned circuit 3 may be larger than that of the secondary circuit 4.

70 The operation of the circuit is as follows. So long as the peak detector input voltage E is less than the negative bias voltage, $E_1 - E_3$, on the anode A₂, there will be no rectification of the impressed voltage E by the diode A₂-K. Nor will there be any incidental rectification of radio 75 voltages in the triode amplifier circuit since the

filter, resistance 9 and condenser 10, prevents radio voltages from reaching grid G.

5 The voltage E_1 due to plate current flow with no input to the amplifier elements is relatively high and transmission of any audio frequency signals by the amplifier is effectively suppressed. When the peak voltage E exceeds the negative bias on anode A₂, rectification takes place and the direct current and audio frequency voltages developed across resistance 6 are impressed on 10 the grid G. The rectified direct current voltage increases the negative bias on grid G, thus reducing the plate current and thereby reducing the voltage E_1 . This reduces the delay action bias 15 voltage on anode A₂, and reduces the negative bias on grid G to a value appropriate for audio bias amplification.

20 Turning now to the automatic gain control, the delay action bias voltage on anode A₁ is equal to E_1 . As soon as rectification takes place in the detector diode circuit, the voltage E_1 is reduced by the direct current amplifier action of the triode elements and the delay bias is thus removed from the automatic gain control diode. The rate at which a gain control voltage is 25 developed, with increasing radio input voltage E, is therefore more rapid than is the case when a fixed delay bias voltage is impressed upon the gain control rectifier. This method of and circuit arrangements for removing the delay bias impressed on a gain control rectifier are described and claimed in my copending application Ser. No. 641,279, filed November 4, 1932.

30 It will be noted that the tuned circuit 4 provides greater selectivity in the transmission of amplified radio voltages to the detector A₂-K than the selectivity of transmission to the rectifier A₁-K. The radio input E to the detector therefore decreases more rapidly than the radio input E to the rectifier when the amplifier 1 is detuned from 35 resonance at the frequency of a received carrier wave. The audio output falls off rapidly when the receiver is detuned and the actual selectivity of the receiver is not materially affected by the automatic gain control. The previous types 40 of gain control systems did not exhibit this difference in the selectivity of transmission to the rectifier and to the detector, and the amplifier gain therefore increased at a rate which approximately compensated for the decrease in 45 radio input to the detector. The response from local stations was thus maintained approximately constant over a wide tuning range as detuning from a strong signal resulted in an automatic increase in sensitivity which counteracted the decrease in audio output which would normally 50 follow from the selectivity characteristics of the tuned amplifier. The differential transmission obtained by means of the Fig. 1 circuit prevents the gain from rising at such a rate as to destroy 55 the selectivity of the amplifier.

60 The detector-control stage illustrated in Fig. 2 functions in the same manner and those circuit elements which are, or may be, identical with those described above are identified by like reference numerals. The input to both diodes is derived from the tuned secondary circuit 4, the input E_0 to the anode A₁ being taken off at higher voltage point, through condenser 19', than that 65 of the input voltage E to anode A₂. As described and claimed in the last named application, the audio output from tube 5 may be taken across the resistance 16, or between the grid G and ground since the audio voltage across the resistance is in 70 75

phase with the voltage on grid G. The switch 24 with its contacts, connected respectively to the cathode end of resistance 16 and to the grid, provides means for establishing these alternative connections. The condenser 17' is, of course, a radio frequency by-pass around resistance 16 and not, as in the Fig. 1 circuit, an audio by-pass for reducing the audio resistance in series with the audio transformer primary.

10 In both circuits, the filter comprising resistance 18 and condenser 17 reduces degeneration in the audio amplifier portion of the tube.

The following values of the principal circuit elements were used in an embodiment of the Fig. 1 circuit which was employed as the second detector of a superheterodyne receiver.

Resistance 6=200,000 ohms

Resistance 9=100,000 ohms

Resistance 16=15,000 ohms

Resistance 18=50,000 ohms

Resistance 20=1 megohm

Resistance 21=500,000 ohms

Condensers 7, 17=0.5 microfarads

Condensers 8, 10, 18=100 micromicrofarads

Condenser 22=0.05 microfarads

Condenser E₂=250 volts

Condenser E₃=60 volts

The inductance of circuit 3 was 18 millihenries and that of the secondary circuit 4 was 4.5 millihenries.

The invention is not limited to the use of the relative values of this particular example, nor, in its broader aspects, to the use of a single tube in the combination detector-control-amplifier stage.

I claim:

1. In a radio receiver, an automatic control system comprising a pair of rectifiers, input means for impressing radio voltages upon each rectifier, an output circuit for each rectifier, means impressing bias voltages upon each rectifier to render the same inoperative for radio input voltages of less than predetermined values, and means energized by the rectified output of one rectifier for automatically reducing both bias voltages when the input on said one rectifier rises above the predetermined value below which no rectification obtains.

2. In a radio receiver, a diode detector, a diode rectifier forming part of an automatic transmission control system for said receiver, an amplifier for amplifying the rectified direct and alternating current voltages developed by said detector, a resistance in the plate circuit of said amplifier, means including said resistance for impressing upon said detector and rectifier delay bias voltages which vary with the plate current flow, the bias voltage initially impressed on the detector being of a magnitude to prevent rectification for all detector input voltages below a predetermined value, and means for impressing on said rectifier a radio input voltage less than and proportional to the radio input voltage on the detector.

3. In a radio receiver, the combination with a tube having two anodes, a control grid, a plate

and a cathode, of a radio frequency amplifier and circuit elements coupling said amplifier to said anodes and cathode to form radio input circuits of a diode detector and a diode rectifier, an output circuit for said diode detector and coupled to said amplifier to impress thereon the rectified direct and alternating current voltages developed by said detector, said output circuit including a resistance across which the flow of amplifier plate current establishes a potential drop that tends to place a negative bias on the detector anode, an output circuit for said diode rectifier, means coupling the rectifier output circuit to said radio frequency amplifier to apply thereto a bias voltage, and means for biasing the rectifier anode by the direct current potential drop across said plate circuit resistance.

4. In a radio receiver, the combination with a radio amplifier, and a detector, of means including a diode rectifier for automatically controlling the gain of said amplifier as a function of the strength of received signals, an input circuit for impressing upon said diode rectifier a radio voltage developed by said radio amplifier, means initially impressing upon said diode rectifier a bias voltage which renders the same inoperative for impressed radio voltages having voltage peaks of less magnitude than said impressed bias voltage, and means energized by a rectified voltage passed by said detector and operative when the rectified voltage exceeds a predetermined value to remove from said rectifier the bias voltage which renders the same inoperative.

5. In a radio receiver, a radio frequency amplifier, a detector working out of said amplifier, means biasing said detector to render the same inoperative for radio input voltages below a critical value, normally inoperative means including a rectifier working out of said amplifier for automatically controlling the gain of said amplifier, and means energized by a rectified voltage developed by said detector for rendering said automatic control means operative.

6. The invention as set forth in claim 5, wherein in the rectifier of said automatic control means is normally biased to render the same inoperative, and said last means comprises an impedance across which a potential drop effective to remove said normal bias is established when said detector passes a rectified voltage of predetermined magnitude.

7. In a radio receiver, the combination with a radio amplifier, a detector, a direct current amplifier working out of said detector, and a resistance in the output circuit of said direct current amplifier, of a diode rectifier having a radio input circuit coupled to said radio amplifier, said resistance being included in its input circuit to impress thereon a bias voltage which varies with the output of said detector, a second resistance in the output circuit of said diode rectifier, and a circuit connection for impressing the variations of direct current potential developed across said second resistance upon said radio amplifier as a gain control bias.

PAUL O. FARNHAM.
